FIG. 1.

FIG. 3.

FIG. 2.

ARTHUR ZADEK
INVENTOR

BY *John*

ATTORNEY

Patented Apr. 13, 1926.

UNITED STATES PATENT OFFICE.

ARTHUR ZADEK, OF NEW YORK, N. Y.

TOY RATTLE.

Application filed December 22, 1925. Serial No. 76,943.

To all whom it may concern:

Be it known that I, ARTHUR ZADEK, a citizen of the United States of America, residing at 57 West 19th Street, city, county, and State of New York, have invented new and useful Improvements in Toy Rattles, of which the following is a specification.

My invention relates to toy rattles and has for its object to provide a rattle of this character with a transparent cylindrical head within which is disposed a holder for supporting a plurality of artificial flowers which are clearly visible from the exterior of the head.

Another object of this invention is to provide the transparent wall of the cylindrical head portion with pastoral scenes through which the enclosed flowers will appear as if in a garden.

The present invention is illustratively exemplified in the accompanying drawing, in which, Figure 1 is a substantially longitudinal sectional view of a toy rattle embodying my improvements; Figures 2 is a transverse sectional view taken on the lines 2—2 of Figure 1; and Figure 3 is a side elevational view of the same.

Referring to the drawings, 10 denotes a substantially upright transparent celluloid head closed at opposite ends by a top and bottom cap 11 and 12, respectively, each of the caps being provided with concentric ribs 13 for the purpose of reenforcing the material. The bottom cap 12 is additionally provided with a projecting collar 14 to which is secured one end of a small cylindrical body 15. The lower or free end of the body 15 is closed by a bottom cap 16 having a substantial center opening 17 to accommodate one end of a handle 18 which projects through the opening and is secured

to the surface of the bottom cap 12. The free end of the handle 18 is arranged to carry a loop 19 in the usual manner.

Secured to the inside face of the bottom cap 12 and concentrically arranged in one of the ribs 13 is the open end of a hemispherically shaped dome or holder 20, the crown of which is provided with an orifice 21 to receive the stems 22 of a number of artificial flowers 23, as clearly illustrated in Figure 1.

It will be clear that the cylindrical head being transparent enables the flowers to be seen from the outside of the toy and in order to carry out the effect of a garden scene I propose to decorate the surface of the cylinder with a line drawing of a fence 24, as illustratively exemplified in Figure 3 of the drawings.

For the purpose of making a rattling noise a number of pebbles or shots 25 are loosely disposed within the cylindrical head.

What I claim and desire to secure by Letters Patent is:—

A rattle having a transparent cylindrical head on the surface of which are arranged line drawings, bottom and top caps for said head, a hemispherical dome secured at its open end to the bottom cap and having an opening in the crown portion thereof, a number of artificial flowers having their stems arranged in said opening and supported by the dome, said flowers being visible through the line drawings on the head, a projecting collar depending from said bottom cap, a second cylinder secured to the said collar, and a handle projecting through said second cylinder and secured to said bottom cap.

In testimony whereof I affix my signature.

ARTHUR ZADEK.
